DRINKING GLASS OR SIMILAR ARTICLE

Jens H. Quistgaard, Copenhagen, Denmark, assignor to Dansk Designs, Ltd., Mt. Kisco, N.Y., a corporation of
New York

Filed Jan. 26, 1970, Ser. No. 21,087

Term of patent 14 years

Int. Cl. D7—01

U.S. Cl. D36—8

FIG. 1

FIG. 2

FIG. 3

FIG. 4

FIG. 5

FIG. 6

FIG. 1 is a top plan view of a drinking glass or similar article showing my new design in the size and proportions of a water goblet;

FIG. 2 is an elevational view thereof;

FIG. 3 is a bottom plan view thereof;

FIG. 4 is a top plan view of a drinking glass or similar article showing my new design in the size and proportions of a champagne or sherbet glass;

FIG. 5 is a side elevational view thereof; and

FIG. 6 is a bottom plan view thereof.

I claim:

The ornamental design for a drinking glass or similar article, as shown and described.
